US00D825955S

(12) **United States Design Patent** (10) **Patent No.:** **US D825,955 S**
(45) **Date of Patent:** **** Aug. 21, 2018**

(54) **PILLOW**

(71) Applicant: **Gemma Jensen**, Altrincham (GB)

(72) Inventor: **Gemma Jensen**, Altrincham (GB)

(**) Term: **15 Years**

(21) Appl. No.: **29/593,789**

(22) Filed: **Feb. 13, 2017**

(30) **Foreign Application Priority Data**

Aug. 12, 2016 (EM) 003340553

(51) **LOC (11) Cl.** **06-09**

(52) **U.S. Cl.**

USPC **D6/601**
